UNITED STATES PATENT OFFICE.

LIONEL M. WOOLSON, OF DAYTON, OHIO, ASSIGNOR, BY MESNE ASSIGNMENTS, TO THE DAYTON ENGINEERING LABORATORIES COMPANY, A CORPORATION OF OHIO.

ELECTRICAL SYSTEM FOR AIRCRAFT.

Application filed November 14, 1917. Serial No. 201,974.

To all whom it may concern:

Be it known that I, LIONEL M. WOOLSON, a citizen of the United States, and a resident of the city of Dayton, county of Montgomery, and State of Ohio, have invented an Improvement in Electrical Systems for Aircraft, of which the following is a specification.

This invention relates to electrical systems for internal combustion engines, and with regard to its more specific features to electrical systems for engines designed for airplane propulsion.

One of the objects thereof is to provide an ignition system involving apparatus of simple, light and rugged construction, specially suitable for modern airplane engines of certain types.

Another object is to provide in apparatus of the above type an ignition system which will function efficiently under all conditions of operation and which is unlikely to break down.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing wherein is shown one of various possible embodiments of the several features of this invention, Fig. 1 is an end view of the engine showing the parts of the ignition system in a preferred relation.

Fig. 2 is a diagrammatic view of the ignition circuits thereof and Fig. 3 is a detail view of the interrupter cams showing their preferred angular relation.

Similar reference characters refer to similar parts throughout the different views of the drawings.

In the specification and claims I intend the term "V-type engine" to apply to any engine in which the axes of some cylinders are at an angle to those of others.

As conductive to an understanding of some of the features of this invention, it may be noted that in airplanes in which, as is well known, the V-type of engine is particularly advantageous, greater efficiency of the vehicle is secured by arranging

the blocks of the V at a relatively small angle, that is at an angle smaller than the average angle between crankshaft positions for successive explosions. This change of angle brings about a reduction in the width of the engine so that a narrower fuselage may be employed with consequent reduction of the resistance of the atmosphere against progress of the vehicle. This alteration of the conventional form of V-type engine makes it desirable to introduce certain changes in the conventional ignition system with a view to securing a high efficiency of action, and one of the objects of the invention as above noted is to bring about such efficiency.

Referring now to Fig. 1 of the drawings, there is shown an eight cylinder engine 1 of the V-type having an angle between its cylinder blocks 2 and 3 of but 45 degrees instead of the angle of 90 degrees, usual in eight cylinder engines of the V-type. The term "block" is used in the specification and claims, without regard to the manner in which the cylinders are cast, the term being used generically as meaning "group of cylinders" regardless of construction. It is obvious that after firing of a cylinder in the left hand block of a four cycle eight cylinder engine of the V-type with its blocks disposed as in Fig. 1, the explosion in the next cylinder in order of firing of the right block, will take place after a 45 degree turn of the crankshaft. Thereupon a turn of 135 degrees of the crankshaft will be necessary before the next explosion will take place in a cylinder on the left hand block, and thus explosions will take place at alternate intervals of a 45 degree turn and a 135 degree turn of the crankshaft, the interval between firing of a cylinder on the left hand block and the next in firing order on the right block being 45 degrees and that between firing of a cylinder on the right hand block and the succeeding one on the left hand block being 135 degrees. The firing order of such an engine is obviously non-symmetrical. In some of the claims forming a part of this specification, I use the term "angle between explosions," to define the angle between crankshaft positions for successive explosions.

A preferred location of the ignition apparatus for the engine is indicated in Fig. 110

1. Mounted substantially centrally between blocks 2 and 3, and near the apex of the V is a current generator 4, driven preferably at twice crank-shaft speed, and having a special construction of timer T, preferably splined on its shaft, as shown at 55, and driven thereby. For reliability of action, two substantially independent ignition systems are preferably provided, both deriving their current from the generator 4. These ignition systems are substantially duplicates, an induction coil 5 being preferably mounted on one cylinder block, and a similar induction coil 6 on the other, there being an eight contact distributer 7 of special construction associated with coil 5, and a similar distributer 8 associated with coil 6. Each cylinder is preferably provided with two spark plugs, some of which plugs are shown by way of example at 15, 16, 15' and 16', making 16 plugs in all for an eight cylinder engine. As shown in the drawing, spark plug 16 is connected to contact 60 on the adjacent distributer and spark plug 15 of the same cylinder is connected to contact 61 of the distributer associated with the other cylinder block. Similarly spark plug 16' on a cylinder of the right hand block is connected with contact 63 of the adjacent distributer, and spark plug 15' of the same cylinder is connected to contact 64 of the distributer 7 associated with the left hand block. In this manner the two spark plugs of each cylinder are connected one with the distributer on the same block and the other with the distributer on the other block. The spark plugs of each cylinder are thus connected to be caused to fire simultaneously, one being energized by way of distributer 7 and the other by way of distributer 8. The connections from each distributer are of course in the same order as the cylinders are designed to fire. The engine as is noted is preferably provided with overhead cam-shafts 17 to which the distributers are attached and by which they are driven.

It may here be noted that the duplicate ignition systems not only furnish protection in case one system should break down in normal operation, but the induction coils and distributers are so spaced that in the case of airplanes used in warfare a small projectile is unlikely to simultaneously cripple both systems. An auxiliary ignition system used for starting is shown mounted at 50. The detailed construction of all of the ignition systems will be more fully described below.

Referring now to Fig. 2, there is shown preferably a generator 4 having main brushes 56 and 57 in neutral position, an auxiliary brush 58 and the field coil 59 connected between brushes 57 and 58, which arrangement will produce substantially constant current with varying speeds. It is to

be understood that other regulating means for this result may be employed to advantage. One of the generator terminals is preferably grounded or connected to a metallic structure of the airplane. The generator leads current to the primary 9 of an induction coil 5 and from there through interrupter contacts 11 back to ground or a metallic structure of the machine, the contacts 11 being bridged by the usual condenser 13 conventionally shown. The interrupter contacts 11 are preferably made to open and close by cam 19 which will be described in greater detail below. The primary coil 9 upon breaking down of the magnetic flux when contacts 11 are opened induces current in secondary 38 and the induced current is led to arm 35 of a distributer 7 of special construction which will be described in greater detail below.

As described above, it is preferable to provide two separate ignition circuits, the second circuit being substantially identical with the first just described, the induction coil 6 having a primary 10 and a secondary 39, the second interrupter being shown at 12 and being bridged by condenser 14 and the second distributer being shown at 8. It is, of course, to be understood that the second ignition circuit may be dispensed with, but there are specially beneficial features of operation resulting from its use.

For reliability of action and in accordance with the peculiar construction of engine above described, the ignition system is preferably designed to produce its ignition sparks at unequal intervals corresponding to crankshaft rotations of 45 degrees and 135 degrees alternately. This is brought about by employing the special construction of cams shown at 19 and 20. These cams are shown in Fig. 3, the cam 19 operating contacts 11 and the cam 20 operating contacts 12. The two cams are substantially identical and operate in synchronism, so that the description below will apply to either. As shown, the operating irregularity 21 which opens the interrupter 11 to produce a spark is succeeded after a 90 degree turn of the cam by operating irregularity 23, the contacts having automatically closed by the action of spring 52 immediately after irregularity 21 passes roller 22. After operating irregularity 23 is passed, the interrupter contacts are maintained opened until axis 25 reaches roller 22 when they again close and again reopen when irregularity 21 reaches roller 22. It is thus seen that the opening of the contacts takes place at alternate intervals of a 90 degree and a 270 degree turn of the cam or, since the generator 4 is operated at twice crankshaft speed these interruptions occur at alternate intervals of 45 degrees and 135 degrees of the crankshaft. It is to be understood that the form of interrupter

130

disclosed is merely by way of example, any desired form of contact being applicable. The distributor 7 and 8 have their respective arms 35 and 36 in synchronism with each other and their contacts are shown to be at alternate angular distances of $22\frac{1}{2}$ degrees and $67\frac{1}{2}$ degrees. Since the distributors are operated by the camshafts and at one-half crankshaft speed, the angles of $22\frac{1}{2}$ and $67\frac{1}{2}$ degrees correspond respectively to angles of 45 degrees and 135 degrees of the crankshaft. It is thus seen that the ignition system disclosed will produce sparks at alternate intervals of 45 degrees and 135 degrees of crankshaft position.

It is to be noted that the angular distance between the closure of the cam at 25 and the irregularity 21 is the same as that between the closure of the interrupter at 26 and the irregularity 23. By this arrangement, a uniform amount of time is allowed for building up of the magnetic flux for the primary coil regardless whether a 45 degree interval of crankshaft rotation or a 135 degree interval precedes firing. The cam in its operation it is seen does not permit a reclosure of the interrupters immediately after irregularity 23 has caused the opening, but it maintains the contacts in open position until point 25 reaches the roller. The cams as is seen are diametrical-ly symmetrical in form. If the interrupter contacts were allowed to close a uniform interval after their opening it is clear that a hotter spark would result after a 135 degree interval than after a 45 degree interval so that the firing of the cylinders of block 3 would be less efficient than that of block 2 bringing about a very undesirable irregularity of action of the engine.

For starting the engine, since the generator 4 does not then operate, a separate source of ignition current for starting should be provided and the spark should preferably be retarded. For this reason, an auxiliary ignition system is provided for the starting operation. This system is preferably of the vibrator type to produce a shower of sparks particularly effective during starting.

Referring to Fig. 1 there is shown a dry or other light battery 27 which is grounded or connected to a metallic structure of the airplane when switch 32 is placed on contact S, and will when contacts 65 are closed lead current through primary coil 28, contacts 65 and back to ground. When interrupter contacts 65 are closed, this induction coil which has the usual vibrator contacts bridged by condenser 52 will open the battery circuit overcoming the resistance of spring 34 upon the magnetic attraction of armature 33 whereupon the spring pulls the armature away from the deenergized electromagnetic coil to reclose the circuit and

the contacts repeat this cycle, vibrating with great rapidity in the well known manner. It is thus seen that while contacts 65 are closed, a succession of impulses is induced in the secondary for producing a shower of ignition sparks as more fully described below.

Cam 18 which operates contacts 65 of the auxiliary ignition system may, as shown, be substantially identical in shape and size with cams 19 and 20, but, unlike the latter, the operating irregularities of cam 18, for reasons just outlined, are the depressions 40 and 41 which bring about closure instead of opening of contacts 35. As shown, these operating irregularities are retarded 90 degrees behind the operating irregularities of cams 19 and 20. The cams 19 and 20 are fixed on the generator shaft with a 90 degree lead with respect to the starting cam, and the cams turning at twice crankshaft speed, cams 19 and 20 will produce a spark advanced by 45 degrees with respect to that produced by starting cam 18.

The secondary 29 of the induction coil leads to a conducting ring 30 on distributor 8 and is by means of this ring 30 brought into electrical connection with a distributor arm 31 maintained preferably non-adjustably $22\frac{1}{2}$ degrees behind the main distributor arm 36 above described. A conducting strip 31' on arm 31 connects ring 30 successively with the distributor contacts. The conducting portion 36' of arm 36 is preferably deflected as shown at 53 to be out of conductive relation with ring 30. Either conducting strip 31' or 36' or both of them are preferably embedded in the insulating material of the corresponding arm to prevent jumping of spark from one strip to the other. Since the distributor rotates at one-half crankshaft speed it is seen that the angular distance of $22\frac{1}{2}$ degrees between distributor arms corresponds to an angle of 45 degrees of flywheel position. If the arms 35 and 36 be properly synchronized with contacts 11 and 12, that is if these contacts are arranged to open the instant the arms each reach a distributor contact, then the ignition circuit for starting will without further adjustment produce a spark retarded 45 degrees behind the normal operating spark. By this arrangement, if the normal operating spark be made to occur at a 45 degree advance, the spark for starting will occur at top dead center of each piston. If as is the case in some types of engine, a spark advance of less than 45 degrees is desired, such adjustment is readily effected. The ignition spark for starting because of its non-adjustable relation of 45 degrees behind the normal operating ignition spark will in such case occur behind top center, which results in efficient operation.

In accordance with the characteris- 130

tics of the engine with which the ignition system is to be employed, the operating ignition circuit is timed to produce a suitable spark advance, which advance may be 6 as great as 45 degrees. Since airplanes are operated at substantially uniform speed no adjustment of the position of ignition spark need be made in the operation of the machine, the advance having once been properly set. The operating ignition circuit 10 having been properly timed, the auxiliary ignition apparatus for starting will without further adjustment operate efficiently 45 degrees behind the main ignition apparatus 15 as above indicated.

The switch 32 has two positions S and O. As described above, when in position S the ignition circuit for starting is closed. When placed in intermediate position indicated by 20 R, this circuit is open, and when in position O, the main brushes 56 and 57 of the generator are short-circuited substantially as in the case of the stopping switch of a high-tension magneto, rendering this generator 25 incapable of producing ignition current. When switch 32 is in any position other than position O, the generator may be operative. A coil spring 66 is preferably located to be compressed when the 30 switch is in position S so that the ignition circuit for starting is closed only when maintained in this position by the hand of the operator.

The construction of the device having 35 been above set forth, the operation is substantially as follows: The airplane driver holds switch 32 in position S, and the engine is thereupon cranked either by hand or by electric or other power. As soon as an irregularity 40 or 41 on cam 18 brings about a closure of contacts 65 the battery 27 will lead current through the primary 28 and cause rapid alternate opening and closure of the primary circuit. The secondary 29 will, 45 therefore, in well-known manner, lead impulses of current to ring 30 and from there through arm 31 in succession to the various cylinders as arm 31 is turned by the cam-shaft. In this manner a shower of sparks 50 will be caused to take place in each cylinder until the engine runs under its own power. When this occurs switch 32 may be allowed to open to place the auxiliary ignition circuit out of action and this switch is then 55 placed in position R. The generator 4 will now be operating with sufficient speed to generate ignition current, and when the simultaneously operating interrupter contacts 11 and 12 are closed, the two main ignition 60 circuits will be closed the one from ground, or a metallic structure of the machine, through the generator, primary coil 9, contacts 11 and back to ground, and the other through primary coil 10, interrupter 12 and 65 back to ground. As soon as the irregulari-

ties 21 or 23 on the cams 19 and 20 cause the interrupters to open, the arms 35 and 36 being then in conductive relation each with a distributor contact, a current impulse will be sent by the secondaries of the induction 70 coils 5 and 6 respectively to the two spark plugs of that cylinder corresponding to the position of the arms. As is readily understood this operation will be repeated at alternate intervals of a 45 degree and 135 degree 75 turn of the crank-shaft resulting in proper ignition. When it is desired to stop the operation of the ignition system, the switch 32 is moved to position O to short-circuit the generator by grounding brush 57. In view 80 of the shape of the cams the time for building up flux for the primary as above described is the same for all cylinders.

If switch 32 is allowed to remain closed after starting, it will merely produce a harmless ignition spark 45 degrees later than the generator spark and nothing objectionable will occur beyond unnecessary depletion of dry battery 27.

As is seen the ignition generator is not 90 supplemented by a storage battery for running, but alone supplies the generative force for the ignition spark. No storage battery holding down the voltage of the generator, the beneficial feature of operation results 95 that as the engine speeds up, the generator produces current at a higher voltage in order to retain the constancy of the amperage, thus obviating the loss in hotness of spark which would result from the lessened time 100 allowed for building up of magnetic flux within the induction coil.

Having reference to distributor 8 shown in the drawing, it is to be noted that by employing the angle of $22\frac{1}{2}$ degrees between distributor arms 31 and 36 and by using the conventional length of arms there will be a distance of not less than $\frac{1}{8}$ inch between the parts of the distributor arm contacts in closest proximity to each other. This distance 110 being the same as that between the distributor contacts which are spaced by $22\frac{1}{2}$ degrees, it is seen that jumping of sparks from arm 31 to 36, or from either arm to a contact other than that designed to be next in 115 order is effectively avoided. This correct operation occurs although the diameter of the distributor is no greater than in the usual commercial single arm type.

If the conventional type of two pole magneto were employed to supply the ignition current it is clear that the same would have to be operated at four times engine speed in order to produce sparks at a 45 degree interval of crankshaft position with the difficulties resulting from such high speed of operation apparent to those skilled in the art.

Although the above description has been applied specifically to a V-type engine hav- 130

ing eight cylinders and having an angle of 45 degrees between the cylinder blocks it is to be noted that this invention is applicable to engines having any number of cylinders 5 compatible with the V-type construction and that any desired angle may be maintained between the cylinder blocks. However, it is to be noted that there are certain specially beneficial characteristics inherent in the specific construction shown and described.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In an eight cylinder V-type internal combustion engine, in combination, two cylinder-blocks arranged at an angle to each other of substantially one-half the average angle between explosions, and an ignition system including an induction coil, and a cam for affecting, said induction coil to build up uniform magnetic flux therein at intervals alternating in the ratio of one to three.

2. In a V-type internal combustion engine, in combination, two cylinder-blocks arranged at an angle to each other of substantially one-half the average angle between explosions, a direct current ignition system including an operating cam having its operating irregularities spaced from each other at alternate angular intervals having the ratio of one to three, and a complementary irregularity preceding each operating irregularity, said complementary irregularities being of uniform length.

3. In an eight-cylinder V-type internal combustion engine, in combination, two cylinder blocks arranged at an angle to each other of substantially 45 degrees, and an ignition system including an interrupter cam driven at twice crankshaft speed and having two circuit interrupting eccentricities spaced at substantially 90 degrees.

4. In an eight cylinder V-type internal combustion engine, in combination, two cylinder-blocks arranged at an angle of 45 degrees to each other, an ignition system including an interrupter cam, driven at twice crankshaft speed, said cam having two op-

erating irregularities 90 degrees apart and said cam being diametrically symmetrical.

5. In an eight-cylinder V-type internal combustion engine, in combination, two cylinders arranged at an angle of substantially 45 degrees to each other, an ignition system including a timer, rotatable at twice crankshaft speed, a distributor rotatable at one-half crankshaft speed, there being two operating irregularities on the cam of said timer, 90 degrees apart, and the distributor contacts being spaced alternately at $22\frac{1}{2}$ degrees and $67\frac{1}{2}$ degrees.

6. In an ignition system for internal combustion engines, in combination, a distributor having a center contact, and a concentric conducting ring contact, an electric generator driven from said engine electrically connected with one of said contacts and a chemical source of ignition connected with the other contact, a distributor arm connected with the same contact as said generator, and a second distributor arm retarded by a definite angle behind said first distributor arm and electrically connected with the other said contact.

7. In a V-type airplane engine, in combination, two cylinder-blocks arranged at an angle to each other of substantially one-half the average angle between explosions, an ignition system therefor, including a source of ignition current for starting, an ignition generator driven from said engine for running, a distributor having the angles between successive contacts thereof alternating in magnitude in the ratio of one to three, said distributor having two arms spaced from each other by an angle substantially equal to the smaller angle between said contacts, the more advanced of said arms being connected to said generator, and the more retarded to said starting source.

8. In an eight-cylinder V-type internal combustion engine, in combination, two cylinder-blocks arranged at an angle of 45 degrees to each other, an ignition system therefor including a source of ignition current for starting, an ignition generator driven from said engine for supplying ignition current during running operation, a distributor having an arm in a position corresponding substantially to dead center position and connected with said starting source, a second arm located for substantially 45 degrees advance, and connected with said generator, said arms being non-adjustable with respect to each other, whereby the angular distance between said arms is equal to the smaller of the angular distances between distributor contacts.

9. In a V-type internal combustion engine, in combination, two cylinder-blocks arranged at an angle to each other of substantially one-half the average angle between explosions, an ignition system having two

substantially identical timers, the interrupter cams thereof having their operating irregularities spaced from each other by angles alternating in magnitude in the ratio 5 of one to three, one of said timers being angularly advanced with respect to the other.

10. In an eight cylinder V-type internal combustion engine, in combination, two cylinders arranged at an angle of substantially 45 degrees to each other, an ignition system including a current generator driven at twice engine speed, two timers mounted on the axis of said generator, each timer 15 cam having two operating irregularities substantially 90 degrees apart, and being diametrically symmetrical, the more retarded cam being employed during starting, and the more advanced during running 20 operation.

11. In a V-type internal combustion engine, in combination, two cylinder-blocks arranged at an angle to each other of substantially one-half the average angle between 25 explosions, an ignition system including two timer cams each having its operating irregularities spaced from each other at angles alternating in magnitude in the ratio of three to one, a distributor having 30 its contacts spaced from each other at angles alternating in magnitude in the ratio of three to one, said timer cams being angularly spaced from each other, and said distributor having two rotatable contacts 35 spaced at an angle corresponding to that between the cams.

12. In an eight cylinder V-type internal combustion engine, in combination, two cylinder-blocks arranged at an angle to each 40 other of substantially 45 degrees, an ignition system including two substantially identical and coaxial timer cams rotating at twice crankshaft speed, each cam having two operating irregularities spaced at an 45 angle of 90 degrees and the cams being angularly spaced with respect to each other for operation 90 degrees apart, a distributor rotatable at one-half crankshaft speed, and having eight contacts, alternately spaced 50 from each other at angles of 22 $\frac{1}{2}$ degrees and 67 $\frac{1}{2}$ degrees, said distributor having two conducting arms spaced at 22 $\frac{1}{2}$ degrees, an induction coil having its primary interrupted by the more advanced cam, and its 55 secondary leading to the more advanced distributor arm, and a second induction coil, having its primary interrupted by the more retarded cam, and its secondary leading to the more retarded distributor arm.

13. In an eight cylinder V-type internal combustion engine, in combination, two cylinder-blocks arranged at an angle to each other of substantially 45 degrees, an ignition system, including a substantially 60 constant current generator located between

the blocks, and driven at twice crankshaft speed, two substantially identical timer cams rotatable with the shaft of said generator, each of said cams having two operating irregularities spaced at 90 degrees from each other, said cams being diametrically symmetrical and displaced with respect to each other for operation 90 degrees apart, a distributor mounted on a camshaft of the engine, said distributor having eight contacts alternately spaced from each other by 22 $\frac{1}{2}$ 70 degrees and 67 $\frac{1}{2}$ degrees, and two distributor arms spaced by 22 $\frac{1}{2}$ degrees, the more advanced cam and the more advanced 75 arm being synchronized.

14. In an eight cylinder V-type internal combustion engine, in combination, two cylinder-blocks arranged at an angle to each other of substantially 45 degrees, an ignition system, including a substantially constant 80 current generator located between the blocks and driven at twice crankshaft speed, three substantially identical timer cams rotatable with the shaft of said generator, each of said cams having two operating irregularities 85 spaced at 90 degrees from each other, said cams being diametrically symmetrical, one of said cams being angularly retarded for operation 90 degrees behind the other two, two substantially identical distributors, 90 one driven from each cam shaft, said distributors having eight contacts alternately spaced from each other by 22 $\frac{1}{2}$ degrees and 67 $\frac{1}{2}$ degrees, one of said distributors having two arms spaced by 22 $\frac{1}{2}$ degrees, the 95 more advanced cam being synchronized with the more advanced of the latter two arms, and the other cams being synchronized one 100 with each of said other arms.

15. In an ignition system for internal 105 combustion engines, in combination, a plurality of ignition circuits and a substantially constant current generator connected with each of said ignition circuits, said circuits consuming the entire output of said 110 generator as it is generated.

16. In a V-type airplane engine, in combination two cylinder blocks arranged at an angle to each other of less than the average angle between explosions, an ignition 115 system for starting including a primary battery as a source of energy, an ignition system for running operation including an electromagnetic source of energy, said first ignition system having means for deriving a shower of sparks during starting from said primary battery which shower shall be of uniform duration for the cylinders of both blocks, and means for allowing in said electromagnetic system a period for building up of the magnetic flux preparatory to each spark, which has the same value for the cylinders of both blocks.

17. In an ignition system for internal 120 combustion engines, in combination a plu- 125

rality of ignition circuits including induction coil apparatus, a substantially constant current generator connected across said apparatus to supply its entire output there-
5 to as it generates the same, whereby the voltage impressed by said generator upon said induction coil apparatus rises with

speed to maintain the constancy of current for providing a uniform ignition spark at widely varying engine speeds.

10

In testimony whereof, I have signed my name to this specification this 9th day of November 1917.

LIONEL M. WOOLSON.
